UNITED STATES PATENT OFFICE

WILLIAM H. MINER, OF CHAZY, NEW YORK, ASSIGNOR TO W. H. MINER, INC., OF CHICAGO,
ILLINOIS, A CORPORATION OF DELAWARE

HAND BRAKE

Application filed January 6, 1930. Serial No. 418,773.

This invention relates to improvements in hand brakes.

One object of the invention is to provide a simple and efficient hand brake mechanism for railway cars, of the rotary chain winding drum type of rugged design, having relatively rapid takeup at the initiation of the winding operation to take up the slack in the brake mechanism followed by a power multiplying action with corresponding slower winding of the chain to tighten the brakes.

A further object of the invention is to provide a brake mechanism of the character described in the preceding paragraph, especially designed to be mounted on the end wall of a car and operated by a rotary hand wheel, wherein the chain is gripped between two rotary members by which a pull is exerted on the chain to successively take up the slack and tighten the brakes with great force.

A more specific object of the invention is to provide a hand brake mechanism including a pair of rotary members between which the brake chain is gripped and on one of which the chain is wound and is driven by the other member through the interposed chain, the last named rotary member being operated by a hand wheel and each of said members being eccentrically mounted to provide the quick takeup action and final great power action, slippage of said members on the chain being entirely overcome by intermeshing with the links thereof.

Other objects of the invention will more clearly appear from the description and claims hereinafter following.

In the drawing, forming a part of this specification, Figure 1 is a vertical, sectional view through my improved brake mechanism, illustrating the same as mounted on the end wall of a railway car. Figure 2 is a vertical, sectional view, substantially at right angles to the view shown in Figure 1, and corresponding to the line 2-2 of said figure. Figure 3 is a horizontal, sectional view corresponding substantially to the line 3-3 of Figure 1.

In said drawing, 10 designates the vertical end wall of a railway car to which my improved brake mechanism is attached. The

operating mechanism of the brakes is preferably contained within a housing which is secured to the end wall of the car so as to dispose the winding means for rotation about a substantially horizontal axis. The 55 chain of the brake mechanism is indicated by 11 and as will be understood is connected to the brake mechanism proper of the car, not shown.

My improved brake mechanism proper 60 comprises an eccentric winding drum A, an eccentric driving member B, a drive shaft C, a hand wheel D, a ratchet member F and a locking dog G.

As hereinbefore pointed out, all of the operating parts of the hand brake mechanism are mounted within a housing. As shown most clearly in Figures 2 and 3, the housing is of two part construction comprising a back plate 12 and a cover member 13. The cover 70 member 13 has a vertical front wall 14 having the lower end section 15 thereof outwardly offset as shown, thereby providing a pocket in which the ratchet member F and the locking dog G are accommodated. The cover 75 member 13 is provided with spaced vertical side wall sections 16-16 connected at the top by a curved wall portion, as clearly shown in Figure 1. The cover member 13 is provided with three securing lugs 17- 80 17-17. One of the lugs 17 is located at the upper end of the housing while the remaining two project laterally from the lower end portions of the side walls 16 of the cover member. The cover member 13 is secured 85 to the back plate 12 by securing elements extending through the lugs 17, the back plate and preferably also through the end wall 10 of the car to secure the housing to the latter. The securing elements may be of any well known form, and are herein shown as rivets.

The winding drum A is fixed to a relatively short supporting shaft 18 having its opposite ends rotatably mounted in the front wall of the offset portion 15 of the cover member of the housing and in the back plate 12. As shown, the inner end of the shaft 18 is provided with an annular flange portion which is seated within an opening in the back plate 12. The back plate 12 is pro- 100

vided with a boss 19 through which the shaft 18 extends, the boss forming a bearing abutment on the inner side of the winding drum A. The ratchet member F is fixed to the shaft 18 adjacent the drum A, as clearly indicated in Figure 2, and has an inwardly projecting hub portion 120 bearing on the drum and an outwardly extending hub portion 20 which bears on the inner side of the vertical wall of the pocket at the bottom end of the cover plate of the housing. As shown, the shaft 18 is held assembled with the housing by means of a cotter pin extending through the end of the same, a washer being preferably interposed between the cotter pin and the outer face of the vertical wall of the cover plate.

The winding drum is of eccentric form and has an annular guide groove 21 in which the brake chain is accommodated, the groove being defined by spaced annular outstanding ribs along opposite side edges of the drum and an inner wall presenting a series of flat surface portions 121-121. The winding surface of the drum is provided with a plurality of depressions or recesses 22-22 in which alternate links of the brake chain are adapted to seat, and projecting lugs 122 therebetween adapted to engage within the remaining links, thus providing in effect a chain engaging portion which meshes with the links of the chain. The winding surface of the drum A has a substantially straight section 23 at one side thereof and a curved section 24 at the opposite side, the curved section being eccentric with respect to the axis of rotation of the drum. As shown most clearly in Figure 1, the curved section 24 of the winding surface of the drum A approaches the axis of rotation of the drum most closely where it connects with the right-hand side of the straight surface portion 23, as indicated at 25. At the left-hand side of the drum A, as shown in Figure 1, the curved surface section 24 is connected to the straight section 23 by a relatively short portion 26 disposed at an angle to the straight section 23. At the same side, the drum A is provided with a pocket 27 in which the end link of the chain 11 is disposed, a securing bolt 28 extending through the link and the walls of the pocket to anchor the chain to the drum.

The driving member B is of substantially the same design as the winding drum A and is preferably made in the form of a duplicate casting of the same. The driving member or drum B has straight and curved gripping surface portions on opposite sides thereof corresponding to the surfaces 23 and 24 of the drum A respectively and also indicated by 23 and 24. The gripping surfaces 23 and 24 merge at the upper end of said drum B, as shown in Figure 1, the merging portion being indicated by 25 and corresponding in every respect to the portion 25 of the drum A.

The drum B as shown is also provided with a pocket 27 corresponding to the pocket of the drum A, which receives the end link of the chain. As will be evident, the two drum members A and B are interchangeable and one may be substituted for the other.

The winding member or drum B is secured to the drive shaft C, which has the hand wheel D fixed to the outer end thereof. The shaft C has its opposite ends journaled in the back plate 12 and a projecting boss 38 on the vertical wall 14 of the cover plate respectively. The inner end of the shaft C is provided with an annular retaining flange 29 which is accommodated in a recess provided in the plate 12. The plate 12 has an inwardly projecting boss 30 which accommodates the inner end of the shaft C and bears on the inner side of the member B, thereby maintaining this member centered between the front and back walls of the housing and in alinement with the drum A.

In order to limit the rotation of the winding mechanism, the back wall of the housing is provided with a pair of stop ribs 31 and 32, which are so located as to be engaged by a projecting flange 33 on the side of the member B. As shown in Figure 1, the flange 33 is in engagement with the rib 32 thereby limiting the unwinding movement of the members A and B. When the drum B is rotated in a winding direction, that is in a clockwise direction as viewed in Figure 1, the flange 33 will finally engage the rib 31, thus positively limiting the rotation of the member B in a winding direction.

The members A and B are so mounted that the straight portion 23 of the former lies in a horizontal plane and the straight portion 23 of the member B extends vertically when in the released position and so spaced that the brake chain 11 will pass therebetween, the links of which mesh with the recesses 22-22 of the two gripping surfaces of these members. As will be evident, rotation of the member B will thus positively feed the chain 11 by meshing therewith and through the chain effect driving of the winding drum member A.

Backward rotation of the drum A is prevented by the locking dog G which is pivoted between its ends on a pivot pin 34, having its opposite ends mounted in the offset wall portion 15 of the cover member and a projecting lug 35 in alinement with the vertical outer wall of the housing. At the inner end, the dog G is provided with a tooth which cooperates with the ratchet member F in such a manner as to permit rotation of the same in a direction to allow winding of the chain, but preventing rotation thereof in a reverse direction. At the opposite end, the dog G is provided with a hand grip by which the same may be manipulated, the hand grip normally overbalancing the dog so as to urge the tooth

thereof into engagement with the ratchet member F.

The operation of my improved hand brake mechanism is as follows: The normal position of the parts when the brakes are released, is that shown in Figure 1. In winding the brake chain to apply the brakes, the hand wheel D is rotated in a clockwise direction, as viewed in Figure 1, thus effecting rotation of the driving member B in a similar direction. Through rotation of the member B, the chain 11, which is gripped between the same and the periphery of the winding drum A, will be forcibly pulled in a direction to effect tightening of the brakes. Inasmuch as the members B and A both mesh with the chain 11, rotation of the member A is positively effected through the member B by the interposed chain. As the chain 11 is anchored to the member A, the latter acts as a chain winding drum and the chain is wound thereon in the usual manner. At the beginning of the chain winding operation, as shown in Figure 1, the chain is engaged by the gripping surface portion of the member B, which is disposed furthest from the axis of rotation of said member, thereby providing rapid takeup of the chain at this time. Inasmuch as the engaging surface 24 is eccentric with respect to the axis of rotation of the member B, during further rotation of said member, the portions of the gripping surfaces thereof which engage the chain 11 are located nearer and nearer to the axis of rotation, thereby increasing the leverage and applying the brakes with greater force. The eccentric curved surfaces of the two members A and B are so designed that the same will mesh with the brake chain 11 in all relative positions of rotation of said members. During the winding operation, the drum A is held against backward movement by the dog G, as hereinbefore pointed out.

When it is desired to release the brakes, the operator disengages the dog G from the ratchet member F, thereby permitting the chain to unwind. If it is desired to back off the chain at the beginning of the brake releasing operation, the dog G is retracted while the hand wheel is securely held against rotation, after which the hand wheel D is rotated in a counter-clockwise direction, as viewed in Figure 1, thereby effecting rotation in a similar direction of the member B and through engagement of the chain by this member rotation of the drum A in a right-hand or clockwise direction.

From the preceding description taken in connection with the drawing, it will be evident that I have provided an exceedingly simple, efficient, rugged hand brake composed of a minimum number of parts which may be readily and cheaply manufactured. Great economy is effected by providing the two drum members of like design, inasmuch as

both of the same may be formed from a single pattern.

Further, by providing the eccentric arrangement of winding drum and driving member which mesh with the brake chain, a construction is had whereby effective, rapid takeup of the slack in the brake chain at the initiation of the winding operation is had, followed by power multiplying action during the tightening of the brake shoes on the wheels of the car during final application of the brakes.

I have herein shown and described what I now consider the preferred manner of carrying out my invention, but the same is merely illustrative and I contemplate all changes and modifications that come within the scope of the claims appended hereto.

I claim:

1. In a hand brake, the combination with a chain; of a pair of rotary members having gripping surfaces between which the chain is clamped, and to one of which the chain is anchored, each of said surfaces being provided with spaced seats adapted to accommodate the corresponding sides of the chain links; means for rotating the other of said rotary members to thereby wind the chain on the first named member; and means for preventing backward rotation of said members in an unwinding direction.

2. In a hand brake, the combination with a chain; of a pair of similar rotary members between which the chain is gripped and on one of which the chain is adapted to be wound, each of said members having seats for the chain links on the gripping portions thereof; and means for rotating said members to wind the chain.

3. In a hand brake, the combination with a chain; of a rotary chain winding drum; a cooperating rotary driving member, said winding drum and driving member gripping the chain therebetween, each member having a plurality of chain link seats, said seats of said members respectively receiving the opposite sides of the links; and means for actuating said driving member.

4. In a hand brake, the combination with a chain; of a winding drum to which one end of the chain is anchored, the surface of said drum being provided with spaced seats meshing with the chain links; a rotary driving member, said driving member and drum gripping the chain therebetween, said driving member having a gripping surface provided with seats adapted to be brought into opposition to the seats of the drum and in meshing relation with the links of the chain; and means for rotating said driving member.

5. In a hand brake, the combination with a chain; of a pair of rotary members gripping the chain therebetween, each of said members having chain link seats meshing with alternate links of the chain, and the

chain being anchored to one of said members; and means for rotating the other member to effect rotation of the member to which the chain is anchored through means of the interposed chain and wind the chain thereon.

6. In a hand brake, the combination with a chain; of a chain winding drum having the chain anchored thereto; of a second drum, said drums gripping the chain therebetween and having the chain engaging portions thereof provided with spaced link receiving seats meshing with alternate links of the chain; a hand wheel operated shaft to which the second named drum is fixed; a ratchet member rotatable with the winding drum; and a locking dog cooperating with said ratchet member.

7. In a hand brake, the combination with a chain; of a pair of eccentric rotary members between which the chain is gripped and to one of which the chain is anchored; and means for rotating the other of said rotary members to thereby wind the chain on the first named member.

8. In a hand brake, the combination with a chain; of a pair of similar rotary eccentric members between which the chain is gripped and on one of which the chain is adapted to be wound, the member on which the chain is wound having, at the beginning of the winding operation, the chain engaging portion of its gripping surface disposed at a lesser distance from the axis of rotation of said member than the distance between the cooperating chain engaging portion of the other rotary member and its axis of rotation; and means for rotating said members to wind the chain.

9. In a hand brake, the combination with a chain; of a rotary chain winding drum having an eccentric winding surface; and a cooperating driving member also having an eccentric winding surface, said winding drum and driving member gripping the chain therebetween, the cooperating chain engaging portions of the surfaces of said drum and member being so disposed that both of said surfaces are more remote from the axis of rotation of said driving member, at the beginning of the chain winding operation, than at the final tightening operation, thereby effecting a rapid takeup of the brake chain followed by a heavy application of force to effect final tightening of the brakes.

10. In a hand brake, the combination with a chain; of a winding drum to which the end of the chain is anchored, the surface of said drum being eccentric to the axis of rotation thereof and meshing with the chain links; and a rotary driving drum, said driving drum and winding drum gripping the chain therebetween, said driving drum having a gripping surface also disposed eccentric with respect to its axis of rotation and meshing with the links of said chain, the co-operating chain engaging portions of the surfaces of said two drums being so disposed that said surfaces of both drums are more remote from the axis of rotation of said driving drum at the beginning of the chain winding operation than at the final tightening operation, thereby effecting a rapid takeup of the brake chain followed by a heavy application of force to effect final tightening of the brakes.

11. In a hand brake, the combination with a chain; of a pair of rotary members gripping the chain therebetween, each of said members having a gripping surface meshing with the chain links, said surfaces of said members being disposed eccentrically with respect to the axes of rotation thereof respectively, and the chain being anchored to one of said members; and means for rotating the other member to effect rotation of the member to which the chain is anchored through the medium of the interposed chain and wind the chain thereon.

12. In a hand brake, the combination with a chain; of a winding drum having the chain anchored thereto; a second drum, said drums gripping the chain therebetween and having gripping surfaces meshing with the chain links, the gripping surface portion of each drum being disposed eccentrically with respect to its axis of rotation, the cooperating chain engaging portions of the surfaces of said two drums being so disposed that said surfaces of both drums are more remote from the axis of rotation of said driving drum at the beginning of the chain winding operation than at the final tightening operation, thereby effecting a rapid takeup of the brake chain followed by a heavy application of force to effect final tightening of the brakes; a hand wheel operated shaft to which the second named drum is fixed; and ratchet means for preventing backward movement of the chain winding drum.

In witness that I claim the foregoing I have hereunto subscribed my name this 24th day of December, 1929.

WILLIAM H. MINER.
